(57) **CLAIM**

I claim the ornamental design for a retaining wall block, substantially as shown and described.

DESCRIPTION

FIGS. 1-7 illustrate a first configuration of the retaining wall block of the present invention.

FIGS. 8-14 show a second configuration of the retaining wall block according to the present invention.

More particularly, FIG. 1 is a perspective view of the first configuration of the retaining wall block, according to the present invention, with structure shown in broken lines not being a part of the claimed invention.

FIG. 2 is a front elevation view of the retaining wall block shown in FIG. 1, with structure shown in broken lines not being a part of the claimed invention.

FIG. 3 is a rear elevation view of the retaining wall block shown in FIG. 1.

FIG. 4 is a left end view of the retaining wall block shown in FIG. 1.

FIG. 5 is right end view of the retaining wall block shown in FIG. 1.

FIG. 6 is a top plan view of the retaining wall block shown in FIG. 1.

FIG. 7 is a bottom plan view of the retaining wall block shown in FIG. 1.

FIG. 8 is a perspective view of the second configuration of the retaining wall block, according to the present invention, with structure shown in broken lines not being a part of the claimed invention.

FIG. 9 is a front elevation view of the retaining wall block shown in FIG. 8, with structure shown in broken lines not being a part of the claimed invention.

FIG. 10 is a rear elevation view of the retaining wall block shown in FIG. 8.

FIG. 11 is a left end view of the retaining wall block shown in FIG. 8.

FIG. 12 is right end view of the retaining wall block shown in FIG. 8.

(Continued)

FIG. 13 is a top plan view of the retaining wall block shown in FIG. 8; and,

FIG. 14 is a bottom plan view of the retaining wall block shown in FIG. 8.
